UNITED STATES PATENT OFFICE.

THEODORE C. NICHOLS, OF OLYMPIA, WASHINGTON.

DESIGN FOR A SEWING CABINET.

Application filed February 21, 1921. Serial No. 446,955. Term of patent 14 years.

To all whom it may concern:

Be it known that I, THEODORE C. NICHOLS, a citizen of the United States, residing at Olympia, in the county of Thurston and State of Washington, have invented a new, original, and ornamental Design for a Sewing Cabinet, of which the following is a specification, reference being had to the accompanying drawings, forming a part thereof.

In drawings the figure is a view in perspective of a sewing cabinet constructed in accordance with my new design, showing the doors in an open position.

I claim—

The ornamental design for a sewing cabinet as shown.

THEODORE C. NICHOLS.
